UNITED STATES PATENT OFFICE.

ANNIE M. HILLMAN, OF WESTHOFF, TEXAS.

ADJUSTABLE SHADE-HANGER.

1,134,852.

Specification of Letters Patent.

Patented Apr. 6, 1915.

Application filed February 25, 1914. Serial No. 820,982.

To all whom it may concern:

Be it known that I, ANNIE M. HILLMAN, a citizen of the United States, residing at Westhoff, in the county of Dewitt and State 5 of Texas, have invented new and useful Improvements in Adjustable Shade-Hangers, of which the following is a specification.

The invention relates to an improved attachment for window frames comprehending particularly an adjustable shade hanger 10 designed to support the usual curtain pole and shade roller.

The main object of the present invention is the provision of an attachment of this 15 character in which the curtain pole supporting arms are fixed to the window frame and in turn slidably support an adjustable bracket in which the usual shade roller is removably mounted.

20 The invention in its preferred form of details will be described in the following specification, reference being had particularly to the accompanying drawings, in which:—

Figure 1 is a perspective view of the improvement. Fig. 2 is a vertical section of the same. Fig. 3 is a transverse section of the same.

Referring particularly to the accompanying drawings, the improved attachment comprises 30 duplicate guides 1 and 2 formed at their lower ends with offset portions providing securing plates 3 and bent at their upper ends to provide duplicate securing plates 4 and terminally projected beyond the securing 35 plates at right angles to the main length of the guide as at 5, the forward terminal being bent to form semi-circular depressions 6 for the reception of the curtain pole. The guides are formed intermediate 40 their lengths with laterally disposed offset supporting plates 7, through the medium of which, together with the supporting plates 3 and 4, the guide is secured to the window frame in a manner to space the main length 45 of the guide from the surface thereof.

The shade supporting bracket includes two members 8 and 9 each composed of sections 10 and 11 arranged at right angles. The upright section 10 is formed with laterally projected spaced plates 12 to slidably engage one of the guides 1 or 2, one of the plates being provided with a set screw adapted to engage the underlying guide to lock the sections in desired adjustment 55 longitudinally of the guide. The section 11

of each member extends at right angles to the section 10, and the meeting ends of the sections of the respective members are formed with extensions 13 adapted to be slidably fitted about the opposing section, 60 whereby the respective members are connected for lateral adjustment. The relatively outer terminals of the section 11 of each member are formed with forwardly projecting plates 14 in which are formed 65 recesses 15 of usual form for the reception of the shade roller of ordinary type.

In the use of the device, it is obvious that the guides 1 and 2 may be secured to the window frame in any desired spaced relation and that the shade bracket may be laterally adjusted so that the sections will 70 slidably embrace the guide. The shade may be then adjusted to any position longitudinally of the guides so as to arrange said 75 shade to cover any desired portion of the window.

What is claimed is:—

1. A window shade attachment comprising parallel guides in the form of flat strips 80 arranged so that their outer faces are in a common plane, supporting portions provided upon said guides, and a curtain shade bracket composed of duplicate flat members, each comprising extensions disposed at right 85 angles to each other, each member being mounted with one extension extending longitudinally with respect to the adjacent guide for sliding movement past the same and with its outer face in the plane of the outer faces of both guides, the other extensions of said members being arranged parallel to each other and connected for lateral adjustment, and longitudinally spaced offset portions formed upon the outer edge of the 90 longitudinal extension of each of said members for frictional engagement with the opposite broad faces of the corresponding guide. 95

2. A window shade attachment comprising parallel guides in the form of flat strips arranged so that their outer faces are in a common plane, supporting portions provided upon said guides, a curtain shade bracket composed of duplicate flat members, each comprising extensions disposed at right angles to each other, each member being mounted with one extension extending longitudinally with respect to the adjacent 100 guide for sliding movement past the same 105 110

and with its outer face in the plane of the outer faces of both guides, the other extensions of said members being arranged parallel to each other and connected for lateral 5 adjustment, and longitudinally spaced offset portions formed upon the outer edge of the longitudinal extension of each of said members for frictional engagement with the opposite broad faces of the corresponding 10 guide, and a securing member adjustably

mounted within one of the guide fingers of each bracket member for engagement with the adjacent face of the corresponding guide.

In testimony whereof I affix my signature in presence of two witnesses.

ANNIE M. HILLMAN.
